UNITED STATES PATENT OFFICE

120,495

DESIGN FOR A PIPE COUPLING

William R. Wilson, Detroit, Mich.

Application February 7, 1938, Serial No. 74,935

Term of patent 7 years

To all whom it may concern:

Be it known that I, William R. Wilson, a citizen of the United States, residing in Detroit, in the county of Wayne and State of Michigan, have invented a new, original, and ornamental Design for a Pipe Coupling of which the following is a specification, reference being had to the accompanying drawing, forming part thereof.

The figure is a perspective view of a pipe coupling, showing my new design.

I claim:

The ornamental design for a pipe coupling, substantially as shown.

WILLIAM R. WILSON.
